COIN CONTROLLED LOCKING MECHANISM

Edward W. McCarroll and Henry Hansen, Chicago, Ill.; said Hansen assignor to said McCarroll

Application May 2, 1938, Serial No. 205,516

8 Claims. (Cl. 194—92)

The invention relates to coin-controlled locks. One object of the invention is to improve the construction and operation of coin-controlled locks of that type in which deposit of a coin and the operation of a key are necessary to release the key and permit the depositor to carry it away until such time as he may replace the key in the lock, which type is usually used for coin-controlled lockers or closets for which a service charge is made.

Another object of the invention is to provide a lock of that type which is simple in construction and efficient in use.

Other objects will appear from the detailed description.

The invention consists in the several novel features which are hereinafter set forth and are more particularly defined by claims at the conclusion hereof.

In the drawings: Fig. 1 is a front elevation of a cabinet to which several of the improved locks are applied. Fig. 2 is a perspective of the locking mechanism on its mounting plate. Fig. 3 is a perspective of the bracket which supports the locking mechanism and is detachable from the mounting plate. Fig. 4 is a perspective of a portion of the channel bar between the lockers, which is adapted to receive the mounting plate for the locking mechanism. Fig. 5 is a section on line 5—5 of Figs. 6 and 7. Fig. 6 is a vertical section taken on line 6—6 of Fig. 5. Fig. 6a is a sectional perspective illustrating the lug for holding the bracket in which the coin-controlled locking-mechanism is supported, in the mounting-plate on which the bracket is removably carried. Fig. 7 is a section taken on line 7—7 of Fig. 6. Fig. 8 is a perspective of the latching device for locking the locking bolt for the locker-door against retraction. Fig. 9 is a vertical section through the coin slide illustrating the arm for controlling the dog for locking of the coin-slide against operation until a coin has been deposited. Fig. 10 is a section taken on line 10—10 of Fig. 5 illustrating the normal position of the dog for arresting the said slide. Fig. 11 is a section taken on line 5—5 of Figs. 6 and 7, illustrating the coin-slide after it has been shifted to its lowered position. Fig. 12 is a section on line 12—12 of Fig. 11. Fig. 13 is a front elevation illustrating the device for controlling the latch for the locking bolt illustrating the position of the latch-releasing lever when the locking bolt has been retracted. Fig. 14 is a similar view illustrating the position of the latch-releasing lever after the key has been turned to lock the

locking bolt. Fig. 15 is a similar view illustrating the latch-releasing lever when the key has been reinserted. Fig. 16 is a vertical section through the key-controlled cylinder lock. Fig. 17 is a front view of the portion of the mounting-plate which carries the cylinder lock.

The invention is exemplified in coin-controlled locking mechanism which is mounted on a plate 20 which is provided with rearwardly extending integral side-flanges 21 and is adapted to fit into a suitable recess or cutaway of a channel-bar 22 which forms a standard or part of the framework of the locker cabinet and is usually disposed at the sides or between the tiers of locker-doors 23. Plate 20 is removably held in the standard 22 so that the mounting plate 20 with the coin-controlled locking mechanism thereon, may be placed into and removed from the standard 22. Plate 20 fits in an opening in the front of the standard 22 and is provided at its lower end with a tongue 24, which laps and engages the back face of standard 22 to position the lower end of plate 20 in the opening. At its upper end, plate 20 is held in the opening in the front face of standard 22 by a locking member 26, which is controlled by a key-operable lock 25 and engages the rear edge of the cross-member 80 of a strip which is welded to standard 22. The upper portion of the back face of plate 20 engages the front edge of legs 81 which are integral with cross-member 80, so that when member 26 is engaged with member 80 the plate 20 will be secured in the standard 22. When locking-member 26 is turned downwardly, to clear member 80, the upper portion of plate 20 will be free to swing forwardly until tongue 24 can be moved upwardly and through the opening in the standard 22, to remove the plate 20 and parts thereon from the standard 22. A coin-controlled locking mechanism is used for each locker door 23 of the cabinet. These locks are identical in construction so that a description of one will be applicable to all.

The entire coin-controlled locking mechanism is supported in and by a bracket 27. This bracket is removably secured to the back of mounting-plate 20, so that it may be unitarily removed with the locking mechanism when repair or substitution of the locking mechanism is necessary or desirable. For this purpose, bracket 27 is secured to the back of plate 20 by integral lugs 29 which fit into slots in one of the side-flanges 21 of plate 20 (Fig. 6a), and a lug 30 which is secured to bracket 27 by a thumb-screw 31 and adapted to extend into a slot 32 in the

other side-flange 21 of plate 20. When screw 31 is removed, lug 30 can be withdrawn from slot 32 and then bracket 27 and the parts mounted thereon can be swung backwardly on lugs 29 until the opposite side of the bracket clears the flange 21 in which slot 32 is located and then the bracket can be moved laterally to withdraw lugs 29 from the slots in the opposite flange 21. This permits the bracket 27 and the locking mechanism mounted thereon to be unitarily removed from plate 20 for replacement or repair. By reverse manipulation of the bracket, it can be placed and secured on the back of the mounting-plate.

The locking mechanism for each door 23 comprises a laterally slidable bolt 34, which extends through one of the flanges 21 of mounting plate 20 and into a suitable slot on said door, and a cylinder lock 35 of any suitable construction which is operable by a key 36.

Bracket 27 comprises a member 27^a, the front face of which fits against the back face of mounting plate 20 and a member 27^b which projects rearwardly and approximately at right angles from member 27^a. Bolt 34 is slidably mounted in bracket member 27^a and cylinder-lock 35 extends rearwardly from, and is mounted in, bracket member 27^a.

A coin-receiving and shifting slide 38 is slidable in a vertical guide-channel 37 formed in bracket member 27^b which extends at right angles to the front-wall of the mounting-plate 20. A lever 39 is fixed by a nut 40 to rotate with the barrel of cylinder lock 35 and comprises an arm 39^a, the terminal of which is extended into a slot 41 in bolt 34 for shifting the bolt through the cylinder lock and an arm 39^b which extends into a slot 42 in the coin-slide 38 for shifting said slide when the barrel of the cylinder-lock is rotated. Bracket-member 27^a is provided with an arcuate slot 44 to permit arm 39^a of lever 39 to slide bolt 34 in said member and bracket-member 27^b is provided with an elongated slot 45 for permitting arm 39^b of lever 39 to swing for shifting slide 38.

The lever 39 serves to operate the bolt 34 and coin-slide 38. The coin-controlled means for controlling the operation of the coin-slide and bolt 34 through lever 39, comprises a dog 46 which is pivoted at 47 to bracket-member 27^b, is provided with a terminal 46^a, which is adapted to enter a slot 49 in coin-slide 38, has an abutment 46^b which is adapted to engage a coin *x* held in the coin-slide, is normally pressed by a spring 48 to swing toward the coin-slide, and is integral with an arm 56 which extends through a slot in one side of bracket-member 27^b, and is adapted to ride on the coin-slide and to extend into a vertical slot 57 in said slide. Normally lever 46 and arm 56 are in the positions illustrated in Figs. 9 and 10, at which time arm 56 will engage one face of coin-slide 38 to hold terminal 46^a out of engagement with the coin-slide and abutment 46^b will be out of channel 37 to permit a coin to drop into the channel into position to be arrested by abutment 53^a on the coin-slide. A hook-shaped cam 56^a is pressed by a spring 56^b so as to extend under the lower end of coin-slide 38 and press the slide upwardly into the normal position illustrated in Figs. 6, 9 and 10. The slide when lowered swings cam 56 against the force of spring 56^b out of the path of the slide. When lever 39 is rotated by the key 36 in the cylinder lock, the coin-slide 38, after it has been moved a short distance, will release

5 arm 56 and permit the slide to press arm 56 into slot 57 in the coin-slide, whereupon the terminal 46^a of dog 46 will be pressed by spring 48 into slot 49 in the coin-slide and arrest the coin-slide against further movement and also prevent bolt 34 from being shifted into its locking position, unless a coin has been deposited in the coin-slide.

A coin-insertion slot 50 extends through 10 mounting-plate 20 and bracket-member 27^a, for edgewise deposit of a coin. Slot 50 communicates with a channel 37 in bracket-member 27^b which extends in the plane of the coin-slide 38. A coin-pocket or recess 53 is formed in the front 15 portion of coin-slide 38 to receive the coin from slot 50 and retain it in channel 37. The lower end of the pocket 53 terminates in a shoulder 53^a, which coacts with a shoulder 53^b on bracket-member 27^b to hold the deposited coin in the 20 position illustrated in Fig. 5. The upper end of the coin-pocket terminates in a shoulder 53^c which is adapted to abut against the coin and positively shift it downwardly to discharge the coin from channel 37.

25 When a coin has been deposited through slot 50 and is arrested by shoulder 53^a on the coin-slide and shoulder 53^b, and the key 36 is turned to shift bolt 34 into its locking position, the coin will arrest abutment 46^b on dog 46 and prevent 30 the dog from entering slot 49 and arresting the coin-slide. As a result, the coin-slide 38 will be free to be shifted downwardly by lever 39 a sufficient distance to permit said lever to shift bolt 34 into its fully-extended locking position to lock 35 the locker-door 23. The coin-slide will be shifted into position illustrated in Fig. 11, at which time the coin *x* will be held by a straight edge 53^e and the flange 24 on the mounting-plate 20 until the coin-slide is retracted to its normal position.

40 In practice, the depositor is required to withdraw the key before making it possible to unlock the cabinet and to prevent the repeated locking and unlocking of the cabinet by the key 45 without requiring payment of a coin for each use. For this purpose, a latch 60 which is pivoted at 61 to the inner face of bracket-member 27^a, has a terminal which extends through a slot 62 in the guide for bolt 34 and is adapted to 50 successively enter notches 63 in the upper edge of bolt 34 for preventing retraction of the bolt until the key 36 has been withdrawn from the cylinder-lock 35. Latch 60 is controlled by a lever 64 which is fulcrumed at 65 on latch 60 and comprises an arm 66 to which a spring 67 is applied and a lower terminal 68, which is adapted to be engaged by the key 36. The cylinder of lock 35 is cut away, as at 69, so that terminal 68 is engageable by the key 36. Spring 67 55 presses downwardly on arm 66 to swing lever 64 to the right towards a stop-ledge 27^e on bracket-member 27^a and also through fulcrum 65 presses latch 60 downwardly. When the locker is unlocked, the cylinder lock 35, key 36 and lever 64 60 will be in the position illustrated in Fig. 13. At this time the free end of latch 60 will rest on the upper edge of bolt 34, notches 63 in bolt 34 will be disposed inwardly of said latch and lever terminal 68 will be disposed at one side of an abutment 36^a on key 36. During the turning of key 36 to the left from the position shown in Fig. 13, to its vertical position to fully project the bolt 34, one face of abutment 36^a on key 36, which is exposed in the cutaway 69 of the rotatable barrel of lock 35, will engage the right-hand 65 70 75

edge of lever terminal 68 and swing lever 64 to the left without disengaging the latch from bolt 34, as illustrated in Fig. 14. As a result, latch 63 will successively drop into notches 63 and prevent retraction of bolt 64 during its shift to, and when it has been shifted into, its projected or locking position. Bolt 34 will then be locked by latch 60 against retraction by the key so that the cylinder can not be reversely rotated. This prevents the user from retracting the bolt 34 until the key 36 has been withdrawn from lock 35.

When key 36 is withdrawn from lock 34, terminal 68 will be pressed to swing into its vertical position against stop-ledge 27^e so its lower end will project across the key-slot in lock 35. When the key is next inserted in lock 35, the inclined inner end of abutment 36^a on the key will engage the lower end of lever terminal 68 and lift the lever so it will swing latch 60 upwardly and withdraw it from notch 63 so that the bolt 34 will be released, as illustrated in Fig. 15. The lock 35 will then be free to be reversely rotated by the key to retract bolt 34 and coin-slide 38 into their respective normal positions. The depositor will then turn key 36 and lock 35 to retract bolt 34. During this rotation, the abutment 36^a of the key will pass away from the lower edge of terminal 68 and then into position shown in Fig. 13. Spring 67 will then force lever 64 downwardly into the position illustrated in Fig. 13 and the latch will be operative for the succeeding operation of lock 35 to project bolt 34.

When the coin-slide 38 is lifted to its normal position (Fig. 5), straight edge 53^e on the slide will pass above the coin resting on flange 24 and into position shown in Fig. 5, so the coin will be released and discharged in a coin-box usually provided at the lower end of the standard 22. This construction causes the coin to be retained in the channel 37 of bracket 27 while the locker is in use so that an inspector, by unlocking the locking-bolt 26 and removing the mounting-plate 20 and the entire locking mechanism, can inspect the deposited token. If a slug or false token has been deposited, a locking mechanism with a different cylinder-lock or a dummy-plate 20 may be substituted so the depositor will not have access to the locker with the key. The vertical travel of coin-slide 38 is limited by a stop-pin 51, fixed in bracket-member 27^b and extending through a slot 51^a in the coin-slide.

A depending closure-plate 59 on, and slideable with, bolt 34 is movable in a recess 59^a in the outer face of bracket-member 27^a, for closing the coin-slot 50 in plate 20 after the initial turning movement of the cylinder-lock to project bolt 34. Closure-plate 59 locks the slot 50 and prevents the deposit of a second coin until the bolt 34 has been retracted to unlock the locker-door and the coin-controlled slide 38 is back in its normal position.

The standard 22 (Fig. 4) has welded to the inner faces of its side-flanges, a strip or plate which comprises a cross-member 80 and legs 81 to reinforce the standard where it is engaged by the bolt 26 for locking the mounting-plate in the standard. Bolt 26 engages the back of the cross-member 80. Legs 81 project forwardly from the cut-away portions in the side-flange of standard 22 in which the side-flanges 21 of the mounting-plate 20 are confined, so they will be overlapped by flanges 21 of the mounting-plate, and the mounting-plate will be fixedly held against lateral movement in standard 22. This construc-

tion firmly secures the mounting-plate in the standard and reinforces the standard.

The cylinder-lock 35 (Fig. 16) may be of any suitable construction, usually including a barrel 35^d rotatable in the cylinder 35^e and key-shiftable tumblers 35^b slidably mounted in said barrel. The front of the mounting-plate 20 is provided with a circular opening 83 in a forwardly embossed rim 84. A notch 85 (Fig. 17) is formed in rim 84 to permit the member 36^a of the key to pass into the barrel 35^d and a notch 36^e is formed in the key. Notch 85 is located to permit insertion and withdrawal of the key when the bolt 34 is in its locked position. A notch 36^e is formed in key 36 to receive the rim 84 and permit the key to be rotated from the locking position to its unlocked position. The rim prevents withdrawal of the key from the lock 35 except when said lock is turned to shift bolt 34 into its door-locking position.

A counter or register 70 is provided to indicate the number of coins which are deposited and the number of uses made of the locker. This register 70 may be of standard construction and provided with suitable counter-wheels and an arm 71 adapted during each oscillation to step the counter up one point. This register is supported in a bracket 73 which is secured to the back of mounting-plate 20. A bar 72 for operating arm 71 is mounted to slide in a vertical channel in bracket 73 and is provided with a notch 74 for a stud on the end of arm 71 for operatively engaging said arm. A pin 75 fixed in bracket 73 extends into a recess 76 in bar 72 and limits the up-and-down strokes of said bar. At its lower end bar 72 is provided with an abutment 77 adapted to be engaged by an abutment 78 on coin-slide 38 for operating the counter. These abutments provide a lost-motion connection between coin-slide 38 and the register operating bar 72, which avoids the use of springs, and permits a long stroke of the coin-slide 38 to produce a short stroke of said bar. This construction is such that the coin-slide can be readily separated from the register-shifting bar when the locking mechanism is unitarily removed or replaced by manipulation of the bracket 27, as hereinbefore described.

When a coin is deposited through slot 50, it will be retained on shoulders 53^a and 53^e (Fig. 5) and abutment 46^b on dog 46 will then be arrested by the coin and retain the dog so that it can not swing into slot 49 of the coin-slide 38. The depositor then turns key 36 to the left and will, through arm 39^a, slide bolt 34 into its locking position and, through arm 39^b, operate coin-slide 38 downwardly until a full stroke has been imparted to said bolt and slide. During this downward movement of slide 38, pocket 53 in slide 38 will pass below abutment 53^b and the coin will drop to the point where it will be retained by edge 53^e which is formed on the coin slide and flange 24 (Fig. 11) until the coin-slide is lifted to its normal position, when the coin will be discharged into the coin-box. During the downward movement of the coin-slide 38, the side of member 36^a of key 36 (Fig. 14) will engage the lower end of terminal 68 and swing lever 64 on its fulcrum 65.

The operation will be as follows: normally, when the door 23 is unlocked the key 36 will be retained in the cylinder lock 35 by rim 84 of the mounting-plate 20, the notch 36^e on the key 36 being then out of registry with the notch 85. If the key 36 is turned slightly to the left, arm 56

will pass into slot 57 under the influence of spring 48 and terminal 46^a of dog 46 will enter slot 49 and prevent further movement of the coin-slide and rotation of the key and lock 35, against the force of spring 67 without lifting latch 60 from bolt 34. During the out-stroke of bolt 34, latch 60 will drop successively into notches 63 in bolt 34 and lock said bolt against retraction. This will prevent the key 36 from being reversely rotated to retract bolt 34. When key 36 is withdrawn from lock 35, lever 64 will swing into position against ledge 27^c and across the key-slot. When the key is again inserted, its member 36^a will slide under lever 68 and lift fulcrum 65 to swing latch 60 out of the notch 63 and release bolt 34 so that the key 36 can be turned to the right and will, through lever 39, retract bolt 35 and raise the coin-slide 38 to its normal position. When the key is fully turned, its upper portion will pass to the right of lever-terminal 68 and release lever 64 so latch 60 will rest on the upper edge of bolt 34. The coin-slide 38 will be raised to its normal position as the key is thus turned. The mechanism will then be locked to prevent operation until another coin is deposited. During each reciprocation of coin-slide 38, slide-bar 72 will be operated to step the counter up one point.

The invention exemplifies a construction in which all of the parts of a coin-controlled locking mechanism are mounted on an angular bracket, which can be readily removed and replaced from the mounting-plate for repair or inspection, it being only necessary to remove or replace the lug 30 for this purpose. The invention also exemplifies a construction in which the bracket for carrying all of the lock-controlled mechanism is angular and provided with a coin-slide which extends at right-angles to the front-wall of the plate. The invention also exemplifies latching means for the door-locking bolt which is operable directly by the key to prevent retraction of the bolt until after the key has been withdrawn from the cylinder lock. It also exemplifies a simple mechanism for operating the coin-counter from the coin-slide which permits removal of the coin-controlled mechanism independently of the counter-mechanism. It also exemplifies a simple closure for the coin-receiving slot to prevent deposit of a second coin when the locker is in use. It also exemplifies a channel-standard for the locking-plate, which is reinforced and is provided with simple means for preventing transverse movement of the mounting-plate in the standard. It also exemplifies mechanism which is simple in construction, efficient in operation and can be produced at a low cost.

The invention is not to be understood as restricted to the details set forth, since these may be modified within the scope of the appended claims, without departing from the spirit and scope of the invention.

Having thus described the invention, what we claim as new and desire to secure by Letters Patent is:

1. In coin-controlled locking-mechanism, the combination of a front-plate, a supporting-bracket comprising a front-member fitting against the back of the front-plate and a side-member extending substantially rearwardly at right angles to the plate, a key-operable cylinder-lock mounted in the front-member, a locking-bolt slidably mounted in the front-member, means operable by the lock for shifting the bolt, the front-plate being provided with a coin-receiving slot for receiving a coin edgewise, a plate for controlling

the operation of the lock, slidably mounted in the side-member of the bracket and provided with a pocket for receiving the coin from the slot, a connection between the lock and the plate for slidably shifting the plate by the lock, and means, carried by the side-member of the bracket, and controlled by a coin in the pocket, for stopping the movement of the plate and preventing operation of the lock.

10 2. In coin-controlled locking-mechanism, the combination of a front-plate having side-flanges, a supporting-bracket comprising a front-member fitting against the back and between the flanges of the front-plate and a side-member extending substantially rearwardly at right angles to the plate, a key-operable cylinder-lock mounted in the front-member, means operable by the lock for shifting the bolt, a locking-bolt slidably mounted in the front-member, the front-plate being provided with a slot for receiving a coin edgewise, a plate for controlling the operation of the lock, slidably mounted in the side-member of the bracket and provided with a pocket for receiving the coin from the slot, a connection between the lock and the plate, for slidably shifting the plate by the lock, means controlled by a coin in the pocket, carried by the side-member of the bracket for stopping the movement of the plate by the lock and preventing the operation of the lock, and means for removably securing the bracket in the front plate.

3. In coin-controlled locking-mechanism, the combination of a front carrying-plate, a supporting-bracket comprising a front-member fitting against the back of the carrying-plate and a side-member extending substantially rearwardly at right-angles to the plate and having a vertical channel therein, a key-operable cylinder-lock carried by the front-member, a locking-bolt slidably mounted in the front-member, the plate being provided with a coin-receiving slot, coin-controlled mechanism for the lock comprising a coin-slide mounted in the channel in the side-plate and provided with a recess for receiving the coin from the slot, a two-armed lever connected to the lock and to the bolt and the coin-slide for operating the bolt and the coin-slide from the lock, coin-controlled means for controlling the movement of the coin-slide to control the operation of the lock, means for locking the bolt when it is shifted into its locking position by the lock, and means controlled by the insertion of the key in the lock while the bolt is in its locking position for releasing the bolt-locking means.

4. In coin-controlled locking mechanism, the combination of a front carrying-plate, a cylinder lock, a bolt slidably across the back of the front-plate, a connection between the lock and the bolt for shifting the bolt, the front-plate being provided with a slot for receiving a coin edgewise, a vertically slidable coin-plate extending at right angles to the front of the carrying-plate and provided with a pocket for receiving a coin from the slot, a connection between the lock and the plate for shifting the coin-plate, means controlled by the coin-plate for arresting the coin when the bolt is shifted to its locking position by the lock and for releasing the coin when the bolt is shifted to its non-locking position, coin-controlled means comprising an element for locking the coin-plate and the connections between the lock and the bolt and between the lock and the plate against operation, a closure for the slot rigid with the slidable bolt and whereby the slot will be closed

when the plate is in its coin-releasing position and the bolt is in its locking position.

5. In coin-controlled locking mechanism, the combination of a key-operable cylinder lock, a locking bolt, a connection between the lock and the bolt for shifting the bolt into and out of locking position, and coin-controlled mechanism comprising a slidable coin-receiving plate, a connection between the plate and the lock for shifting the plate, a dog for engaging the plate to lock the plate, said connections and the lock against operation, and provided with means engageable by a coin to hold it in its inoperative position, an arm connected to the dog, normally engaging the plate to initially hold the dog released, the plate being provided with means for controlling the arm to render the dog operative when the plate is shifted and the dog is not held by a coin, and means for yieldingly pressing the plate into its normal position.

6. In coin-controlled locking mechanism, the combination of a key-operable cylinder lock, a locking bolt, a connection between the lock and the bolt for shifting the bolt into and out of locking position, and coin-controlled mechanism comprising a slidable coin-receiving plate, a connection between the plate and the lock for shifting the plate, a dog for engaging the plate to lock the plate, said connection and the lock against operation, and provided with means engageable by a coin to hold it in its inoperative position, an arm connected to the dog, normally engaging the plate to initially hold the dog released, the plate being provided with means for controlling the arm to render the dog operative when the plate is shifted and the dog is not held by a coin, and a spring-pressed cam for pressing the plate into its normal position, the plate having a portion for shifting the cam out of its path when a coin has been deposited in the 40 plate and the plate is shifted by the lock.

7. In coin-controlled locking mechanism, the

combination of a front carrying-plate, a supporting bracket removably mounted on the back of the carrying-plate, a cylinder lock carried by the bracket and accessible from the front of the carrying-plate, a plate mounted to slide vertically in the bracket and having a coin-pocket therein, mechanism controlled by a coin in the coin-pocket for controlling the plate, a connection between the plate and the lock for shifting the plate when the lock is operated, a register for the deposited coins mounted on the back of the carrying plate and register-operating means comprising a bar mounted to slide vertically on the carrying-plate, the plate and bar being provided with 10 interfitting abutments which are separable to permit the bracket and the parts carried thereby to be removed independently of the bar.

8. In coin-controlled locking-mechanism, the combination with a front carrying-plate, a cylinder-lock, a locking-bolt slidably mounted to move across the back of the plate, a connection between the bolt and the lock for shifting the bolt by the lock, a slidable coin-plate operable by the lock extending substantially at right angles to the 25 front of the carrying-plate, the front plate being provided with a coin-insertion slot, a connection between the plate and the lock for shifting the plate by the lock, means for arresting movement of the slidable coin-plate by the lock, 30 the coin-plate being provided with a pocket for retaining a deposited coin in position to hold said arresting means inoperative when the coin-plate is shifted from its normal position, and means controlled by the coin-plate for holding the coin 35 after the coin-plate has been shifted by the lock and while the lock remains in locking position and for releasing the coin when the coin-plate is returned to its normal position by the return of the bolt to its normal position by the lock.

EDWARD W. McCARROLL.
HENRY HANSEN.
